INVENTOR.

William Gorman

UNITED STATES PATENT OFFICE.

WILLIAM GORMAN, OF NEW BRITAIN, CONNECTICUT, ASSIGNOR TO THE RUSSELL AND ERWIN MANUFACTURING COMPANY, OF SAME PLACE.

DESIGN FOR DOOR-KNOB ROSE.

Specification forming part of Design No. 7,019, dated December 9, 1873; application filed November 15, 1873.
[Term of Patent 14 years.]

CASE G.

To all whom it may concern:

Be it known that I, WILLIAM GORMAN, of New Britain, in the county of Hartford and State of Connecticut, have invented a new Design for a Rose for a Door-Knob; and I do hereby declare that the following specification, taken in connection with the drawings, is a full, clear, and exact description thereof.

Figure 1 is a front view. Fig. 2 is a side view of said rose.

The distinguishing features of my said design are the alternate arrangement of cinque-foils F, or like figures of leaf-work, and a ball or spot, I, on a stem, a, extending radially from a border, B, of a smaller diameter, and bounded

by a plain border, H, of larger diameter at the margin. If desirable, some of the spots I may be enlarged sufficiently to form a border in relief around the countersunk perforations J, which receive the screws by which the rose is attached to the door.

What I claim as my invention, and desire to secure by Letters Patent, is—

The design for the rose of a door-knob, substantially as shown and described.

WILLIAM GORMAN.
